UNITED STATES PATENT OFFICE.

GARDNER C. LUTHER, OF SWANSEA, MASSACHUSETTS.

DESIGN FOR A SIDE RAIL FOR BEDSTEADS.

SPECIFICATION forming part of Design No. 34,491, dated May 7, 1901.

Application filed April 1, 1901. Serial No. 53,973. Term of patent 7 years.

To all whom it may concern:

Be it known that I, GARDNER C. LUTHER, a citizen of the United States of America, and a resident of the town of Swansea, in the county of Bristol and State of Massachusetts, have invented and produced a new and original Design for a Side Rail for Bedsteads, of which the following is a specification.

This invention relates to a new and original design for a side rail for bedsteads; and it consists of a side rail of the shape and configuration shown in the accompanying drawings, in which—

Figure 1 is a perspective view of the side rail, and Fig. 2 is a cross-section of the same.

The leading features of the design comprise a side rail having a comparatively broad or deep side *a*, upper and lower ribs or flange

members *a' a'*, extending at angles from the face of said side *a* and longitudinally therewith and forming a channel-shaped girder, the oppositely-disposed upper and lower vertical end extensions *b b'*, respectively, a rearwardly-extending plate *c* at each end of the side rail having its outer portion bent at right angles therewith and parallel with the face of the rail to form flat surfaces *d*.

What I claim is—

The design for a side rail for bedsteads, as herein shown and described.

Signed at Providence, Rhode Island, this 30th day of March, 1901.

GARDNER C. LUTHER.
